SLOTTING APPARATUS

Lloyd L. Miller, Cranford, N. J., assignor to Western Electric Company, Incorporated, New York, N. Y., a corporation of New York

Application September 4, 1942, Serial No. 457,367

2 Claims. (Cl. 144—253)

This invention relates to slotting apparatus, and more particularly to apparatus for producing wire receiving slots in spool heads.

An object of the invention is to provide a simple, efficient and highly practical apparatus for cutting slots in articles.

With this and other objects in view, the invention comprises a slotting apparatus having driven spindles for slotting elements driven in given directions and mounted to position the elements within open portions of a guide through which the articles to be slotted may be advanced, means being provided to eliminate vibrations of the articles during the slotting operation.

Other objects and advantages will be apparent from the following detailed description when considered in conjunction with the accompanying drawing, wherein

Fig. 1 is a fragmentary top plan view of the apparatus;

Fig. 2 is a vertical sectional view of the structure shown in Fig. 1, this section being taken substantially along the line 2—2 of Fig. 1;

Fig. 3 is a fragmentary sectional view taken substantially along the line 3—3 of Fig. 2, and

Fig. 4 is a perspective view of a portion of one of the articles after the slotting operation has been completed thereon.

Referring now to the drawing, attention is first directed to Figs. 1 and 2, which illustrate a base 10 upon which a lateral support 11 is mounted through the aid of screws 12. Channel members 14 are mounted upon the support 11. Upon the channel members 14, a plurality of supporting brackets 15, 16 and 17 is rigidly mounted through any suitable means (not shown). The supporting brackets 15 and 16 have brackets 18 and 19 respectively disposed thereon and adjustably secured thereto by their respective screws 20 and 21, the screws extending through elongate apertures 22 in the brackets. The brackets 18 and 19, through cooperating clamps 24 and 25 respectively, support air operated motors 26 and 27 respectively, which may be provided with air under pressure from any desired source (not shown).

The motors 26 and 27 have tool supporting chucks 28 and 29 respectively for removably supporting their spindles 30 and 31. As shown in Fig. 3, the motors together with their other parts are mounted at spaced positions both laterally and vertically so that their spindles 30 and 31 are parallel with each other in a vertical plane. Pairs of slotting elements 32 and 33 are mounted upon the spindles 30 and 31 respectively, these

elements being removably held on their spindles by the aid of nuts 34. It will also be apparent, by viewing Fig. 3, that the elements 32 and 33 are in parallel pairs.

The bracket 17 extends vertically adjacent the slotting elements 32 and 33 and has a cutaway portion 36 to receive the elements 32. A tubular guide 38 is supported by the bracket 17 and has cutaway portions 39 and 40 for the elements 32 and 33 respectively. The guide 38 is in alignment with a trough 41 of a table 42 through which articles such as spools 43 having heads 44, may be axially advanced relative to the slotting elements. A spring or resilient member 46 has an end 47 secured in place upon the tubular guide 38, the central portion lying in an arcuate contour in the cutaway portion 40 while a free end 48 rests upon the rearward end of the guide. By viewing Fig. 3, it will be observed that the resilient member is positioned between the two slotting elements 33 and rests upon the heads of the articles passing between the sets of shearing elements to hold them against vibration or movement out of their axial paths during the slotting operation. The table 42 is supported by a pair of uprights 50 and may be of any desired length, with the trough 41 therein, for supporting, upon either or both sides of the trough, supplies of the articles which are to be fed in the trough through the guide to the slotting elements.

To condition the apparatus for operation, all that is necessary is to cause energization of the motors 26 and 27 after the support has been set up to perform the desired operations. By the term "set up" is meant the mounting of the elements 32 and 33 upon their spindles with desired spacers 51 to space the elements desired distances apart. Another feature which may be considered in setting up the apparatus, is the relative positions of the slotting elements. In the present instance the pairs of slotting elements are aligned; in other instances it may be desired to have the slotting elements out of alignment with each other. This may be accomplished by adjusting the brackets 15 and 16 relative to each other and the bracket 17 by loosening the screws 20, the adjustment being made possible through the aid of the elongate apertures 22.

Assuming now that the elements 32 and 33 are being driven counterclockwise and clockwise, respectively, (Fig. 2), the articles 43 may be placed in the trough 41 and moved axially therein, their continued advancement carrying them into the tubular guide 38 and eventually between the sets

of slotting elements 32 and 33. In passing between the slotting elements the articles are partially supported by the tubular guide and by the slotting elements. By viewing Fig. 2, it will be noted that the rearmost head of one article has just been slotted and the foremost head of another article is being slotted. The opposite heads of these articles are supported by the tubular guide. The heads being slotted are further supported by arcuate side portions of the guide 38 between the cutaway portions 39 and 40. This is apparent by viewing Fig. 3; thus the heads being slotted are not dependent upon the elements for their support but receive continued support by the guide 38. The resilient member 46 functions to eliminate vibration of the articles during the slotting operation, which might occur if the articles should be advanced too rapidly and if they were not supported during the slotting operation.

As a result of the slotting operation, it will be observed that four spaced slots are formed in the heads of the articles, these slots being formed simultaneously, and during their forming, the pressures of the slotting elements tend to counterbalance the force of each other, there being upward pressure by the elements 32 counteracted by the downward pressures of the elements 33. After the slotting operations have been completed on the articles during their advancement, the articles may drop into any suitable receptacle (not shown).

Although specific improvements of the inven-

tion have been shown and described, it will be understood that they are but illustrative and that various modifications may be made therein without departing from the scope and spirit of this invention as defined by the appended claims.

What is claimed is:

1. A slotting apparatus comprising opposed rotatable slotting elements for successively cutting aligned groups of slots in heads of spools parallel with the axes of the spools, a tubular guide to successively receive and support the spools during their advancement to and between the cutting elements and having opposed cutaway portions to receive the elements, and a resilient member extending through one of the cutaway portions in the tubular guide to engage the spool heads at the elements to hold the spools against vibrating during slotting of their heads.
2. A slotting apparatus comprising pairs of parallel rotatable slotting elements mounted at spaced positions for successively cutting equally spaced parallel slots in the peripheries of heads of spools, a tubular guide to successively receive and support the spools during their advancement to and between the cutting elements and having opposed cutaway portions to receive the elements, and a resilient member extending through one of the cutaway portions in the tubular guide to engage the spool heads between one pair of the elements to hold the spools against vibrating during slotting of their heads.

LLOYD L. MILLER.
